Fig. 1

Fig. 2

FIG. 1 is a perspective view of a reflective hand signal for pedestrians showing my new design.

FIG. 2 is a side elevation thereof.

The sides of the hand signal not shown are substantially the same in appearance as the side shown.

The stippled area shown in FIG. 1 represents a conventional reflective surface.

I claim:

The ornamental design for a reflective hand signal for pedestrians, as shown and described.
